UNITED STATES PATENT OFFICE

EDWARD B. TODT, OF ELKHART, INDIANA

WIND MUSICAL INSTRUMENT

Application filed May 11, 1931. Serial No. 536,604.

This invention relates to wind musical instruments, more particularly to saxophones, and the invention has for its object to provide, in a manner as hereinafter set forth, a 5 saxophone with means for increasing or decreasing the length of the air column for the purpose of tuning the instrument.

A further object of the invention is to provide, in a manner as hereinafter set forth, 10 a wind musical instrument, more particularly a saxophone with a mouthpiece adjustment for the purpose of lengthening or shortening the air column to provide for the tuning of the instrument.

15 A further object of the invention is to provide, in a manner as hereinafter set forth, a wind musical instrument, more particularly a saxophone with a mouth pipe tube having its inner face uniformly tapered 20 throughout for providing and maintaining the correct acoustical proportions.

A further object of the invention is to provide, in a manner as hereinafter set forth, 25 a wind musical instrument, more particularly a saxophone including a mouth pipe tube uniformly tapered throughout its inner face to provide and maintain correct acoustical proportions and with the tube having a portion thereof of uniform outer diameter 30 encompassed by an adjustable mouthpiece carrier and with means for shifting the carrier lengthwise in opposite directions with respect to the tube thereby increasing or decreasing the distance from the mouthpiece to the body of the saxophone for the 35 purpose of tuning the instrument.

Further objects of the invention are to provide, in a manner as hereinafter set forth, 40 an adjustable mouthpiece adjustment for wind musical instruments, more particularly saxophones, which is simple in its construction and arrangement, strong, durable, compact, thoroughly efficient in its use, conveniently adjusted, readily set up and comparatively inexpensive.

With the foregoing and other objects in view, the invention consists of the novel construction, combination and arrangement of parts as hereinafter more specifically described, and illustrated in the accompany-

ing drawings, wherein is shown an embodiment of the invention, but it is to be understood that changes, variations and modifications can be resorted to which fall within the scope of the invention as claimed. 55

In the drawings wherein like reference characters denote corresponding parts throughout the several views:—

Figure 1 is a fragmentary view in side elevation and partly in section illustrating 60 the mouthpiece adjustment in accordance with this invention.

Figure 2 is a fragmentary view in longitudinal section of the mouthpiece adjustment in accordance with this invention. 65

Figure 3 is a cross sectional view of the mouthpiece adjustment in accordance with this invention on line 3—3 Figure 2.

Figure 4 is a perspective view of the adjustable carrier for the mouthpiece. 70

Figure 5 is a longitudinal sectional view of the adjusting element for the carrier.

Figure 6 is a longitudinal sectional view of a modified form of mouthpiece adjustment in accordance with this invention. 75

Figure 7 is a longitudinal sectional view of a modified form of mouth pipe tube.

Figure 8 is a section on line 8—8 Figure 7.

Figure 9 is a longitudinal sectional view of one of the sections of the modified form of mouth pipe tube. 80

Referring to Figures 1 to 5 of the drawings, a combined tube and bearing element is shown and which includes the mouth pipe tube 10 of the instrument and having its inner face 11 uniformly tapered throughout and in a direction whereby the inner diameter of the tube 10 will gradually increase from its forward towards its rear end. The tube 10 intermediate its ends is formed with a peripheral shoulder 12 and that portion 13 of its outer face from the shoulder 12 to the forward end of the tube is of uniform diameter. That portion 14 of the outer face of the tube 10 which extends from the shoulder 12 towards the rear end of tube 10 gradually increases in diameter towards said rear end. Fixedly secured to the outer face of the tube 10 by soldering and flush at its inner end with the shoulder 12 is a bearing sleeve 15 100

having a tapered inner face and its outer face of uniform diameter. The sleeve 15 is formed at its rear end with an outwardly directed right angularly disposed annular flange 16. The sleeve 15 has its outer face formed with a socket 17 adjacent its front end and in which is anchored an outwardly projecting pin 18.

Revolutely mounted on the portion 14 of the outer face of the tube 10 rearwardly of the sleeve 15, is a collar 19 formed with a peripheral shoulder 20 and peripheral threads 21. The collar 19 forms a bearing for the rearward end of and is coupled to an adjusting element to be hereinafter referred to.

Opposing the sleeve 15 and projecting forwardly therefrom is a mouthpiece carrier referred to generally at 22 and of tubular form. The carrier 22 includes a front part 23 of uniform inner and outer diameters, an intermediate part 24 disposed outwardly at right angles to the rear end of part 23 and which terminates in a rear part 25 having an enlarged portion formed with peripheral threads 26. The enlarged portion provides the rear portion 25 with a peripheral shoulder 27. The part 25 is of uniform inner diameter and has its inner face provided with a lengthwise disposed slot 27' extending from the rear edge 28 of part 25 and terminating at a point rearwardly of the intermediate part 24. The front end of part 23 is formed with an outwardly directed right angularly disposed annular flange 29 having its rear face providing an abutment 30. The intermediate part 24 also provides an abutment 31 which opposes the abutment 30. The pin 18 of sleeve 15 is permanently positioned in the groove 27' and slidably couples the carrier 22 with the tube 10.

A revolute adjusting element is provided for the carrier 22 for the purpose of shifting it forwardly and rearwardly with respect to the tube 10 to increase or decrease the length of the air column for the purpose of tuning the instrument. The adjusting element generally referred to at 32, is of tubular form and comprises a body portion 33 having an inwardly extending flange 34 at its front end to provide a shoulder 35. The inner face of body portion 33 in proximity to its rear end is provided with a groove 36 and also with threads 37 which extend from the groove 36 to the shoulder 35. The inner face of body portion 33 is also provided with threads 38 which extend from the groove 36 to the rear end of body portion 33.

The threads 37 of body portion 33 engage with the threads 26 of the carrier 22 for the purpose of shifting the latter. The threads 38 of body portion 33 engage with the threads 21 of the collar 19 for coupling the latter to element 32 whereby the collar 19 will bodily revolve with element 32. The

flange 16 of sleeve 15 extends into the groove 36 of body portion 33 to prevent the longitudinal shifting of the latter relative to tube 10. The flange 16 of sleeve 15 is arranged in the path of the rear end of carrier 22 for arresting the forward movement of the latter. The shoulder 27 coacts with shoulder 35 for arresting the forward movement of carrier 22. The flange 34 of body portion 33 rides upon the reduced portion of part 24 of carrier 22. Surrounding part 23 of carrier 22 and interposed between shoulders 30 and 31 is a cushioning sleeve 39 preferably formed of cork and which couples the mouthpiece 40 to the carrier 22.

In the construction and arrangement of parts as shown a mouthpiece adjustment is provided whereby when the element 32 is revolved in one direction the carrier 22 will be shifted forwardly carrying the mouthpiece 40 therewith and away from tube and under such conditions increasing the length of the air column. When the element 32 is revolved in the opposite direction the carrier 22 will be shifted rearwardly thereby moving the mouthpiece toward the tube 10 and decreasing the length of the air column.

In the form shown in Figures 6 to 9 the carrier is indicated generally at 41 and the adjusting element for the carrier is indicated generally at 42. The carrier 41 and adjusting element 42 are constructed in the same manner as the carrier 22 and adjusting element 32 respectively.

The difference between the form shown in Figures 6 to 9 and that shown in Figures 1 to 5 resides in the manner of setting up the combined tube and bearing element and which comprises a mouth pipe tube 43 formed of a rear section 44 and a forward section. The forward section includes a rear part 45, an intermediate part 46 and a forward part 47. The part 45 is offset with respect to part 47 thereby providing a shoulder 48. The part 45 at its rear end has a right angularly disposed outwardly directed flange 49. The part 45 encompasses the front portion of section 44 and provides a bearing for the forward part of carrier 41. The forward end of section 44 abuts the shoulder 48. The part 45 is fixedly secured to the section 44 by soldering or smelting. The inner face 50 of part 47 is uniformly tapered from its forward to its rear end. The inner face 51 of the section 44 is tapered and the taper is uniform from its forward to its rear end. The tapered inner face 51 of section 44 forms a continuation of the tapered inner face 50 of the section 47. The tube 43 is so set up that when the sections are connected together its inner face will be uniformly tapered from its forward to its rear end. The outer diameter of the part 47 is uniform throughout. The outer diameter of part 45 is uniform throughout. The part 45 in proximity to part 46 carries an out-

wardly directed pin 52 which travels in the groove of the carrier 41 for coupling the latter with the tube 43. The mouthpiece is secured upon the front portion of carrier 41 and the latter shifts forwardly and rearwardly upon the parts 45 and 47 of the tube 43 to move the mouthpiece from and towards tube 43 to decrease or increase the length of the air column.

10 Otherwise than as stated the form shown in Figures 6 to 9 is constructed in the same manner as the form shown in Figures 2 to 5.

15 The adjusting element 32 or 42 is formed at each end with peripheral knurled portions 52' to facilitate the revolving thereof. When the carrier abuts the flange 16 or 49 the front end of element 32 or 42 is flush with the outer side of the intermediate portion 24 of the carrier 22 or 41. The rear part of the carrier 22 or 41 is of a length to permanently project beyond the front end of sleeve 15 or the intermediate part 46. The collar 19 extends rearwardly from the rear end of element 32 or 42. The part 17 of carrier 22 or 41 has a snug 25 sliding fit with sleeve 15 or part 45 respectively.

What I claim is:—

1. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, and a revolute adjusting element encompassing said rear part and said tube rearwardly of said rear part for shifting the carrier lengthwise of and in opposite directions with respect to the tube.

2. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said rear part being

peripherally threaded, and said element threadedly engaging with said rear part.

3. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said carrier and element having coacting means for limiting the shift of the carrier in one direction, and said bearing having means for limiting the shift of the carrier in the other direction.

4. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said rear part being peripherally threaded, said element threadedly engaging with said rear part, said carrier and element having coacting means for limiting the shift of the carrier in the other direction.

5. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, and a revolute adjusting element encompassing said rear part and said

tube rearwardly of said rear part for shifting the carrier lengthwise of and in opposite directions with respect to the tube, said tube provided intermediate its ends with a peripheral shoulder opposing in spaced relation the rear end of said forward part, said tube having its inner face tapered uniformly from its forward to its rear end and having that portion thereof extending from said shoulder to its forward end of uniform outer diameter.

6. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said rear part being peripherally threaded, and said element threadedly engaging with said rear part, said tube provided intermediate its ends with a peripheral shoulder opposing in spaced relation the rear end of said forward part, said tube having its inner face tapered uniformly from its forward to its rear end and having that portion thereof extending from said shoulder to its forward end of uniform outer diameter.

7. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said carrier and element having coacting means for limiting the shift of the carrier in one direction, and said bearing having means for limiting the shift of the carrier in the other direction, said tube provided intermediate its ends with a peripheral shoulder opposing in spaced relation the rear end of said forward part, said tube having its inner face tapered uniformly from its forward to its rear end and having that portion thereof extending from said shoulder to its forward end of uniform outer diameter.

8. In wind musical instruments of the reed type, means to provide a mouth pipe tube having a portion thereof providing a bearing on its outer face, a mouth piece carrier including a forward and a rear part, the latter being of greater diameter than the former and mounted against, encompassing and extending forwardly from said bearing, said forward part being inset with respect to said rear part and mounted against and encompassing said pipe forwardly of the bearing, said carrier being lengthwise shiftable in opposite directions with respect to the tube for increasing and decreasing the length of the air column, a revolute adjusting element encompassing said rear part and said tube rearwardly of said rear part for shifting the carrier lengthwise of and in opposite directions with respect to the tube, said rear part being peripherally threaded, said element threadedly engaging with said rear part, said carrier and element having coacting means for limiting the shift of the carrier in the other direction, said tube provided intermediate its ends with a peripheral shoulder opposing in spaced relation the rear end of said forward part, said tube having its inner face tapered uniformly from its forward to its rear end and having that portion thereof extending from said shoulder to its forward end of uniform outer diameter.

9. In wind musical instruments of the reed type, a mouth piece adjustment including a mouth piece carrier shiftable in opposite directions lengthwise with respect to the mouth piece tube of the instrument and consisting of a forward part for carrying the mouth piece and an outset rear part for slidable connection to the tube and being peripherally threaded for engagement by a shifting element therefor, and bearing means interposed between said rear part and tube.

10. In wind musical instruments of the reed type, a mouth piece adjustment including a mouth piece carrier shiftable in opposite directions lengthwise with respect to the mouth piece tube of the instrument and consisting of a forward part for carrying the mouth piece and an outset rear part for slidable connection to the tube and being peripherally threaded for engagement by a shifting element therefor, bearing means interposed between said rear part and tube, said rear part having a lengthwise groove on its inner face, and a pin extended from the bearing into said groove.

11. In wind musical instruments of the reed type, a mouth piece adjustment including a mouth piece carrier shiftable in opposite directions lengthwise with respect to the mouth piece tube of the instrument and consisting of a forward part for carrying the mouth piece and an outset rear part for slidable connection to the tube and being peripherally threaded for engagement by a shifting element therefor, bearing means interposed between said rear part and tube, said rear part having a lengthwise groove on its inner face, and a pin extended from the bearing into said groove.

- posite directions lengthwise with respect to the mouth pipe tube, said carrier having a forward part for mounting on and a rear part spaced from said tube, said rear part being peripherally threaded, a fixed bearing for said rear part, said bearing and rear part having coacting means for slidably connecting the latter to the former, and a revoluble shifting element for the carrier, said element having threaded engagement with and mounted on said rear part, said element extended rearwardly from said rear part and revolubly mounted on said tube. 5
12. In wind musical instruments of the reed type, a mouth piece adjustment including a mouth piece carrier shiftable in opposite directions lengthwise with respect to the mouth pipe tube, said carrier having a forward part for mounting on and a rear part spaced from said tube, said rear part being peripherally threaded, a fixed bearing for said rear part, said bearing and rear part having coacting means for slidably connecting the latter to the former, a revoluble shifting element for the carrier, said element having threaded engagement with and mounted on said rear part, said element extended rearwardly from said rear part and revolubly mounted on said tube, said bearing having means for limiting the shifting movement of the carrier in one direction, and said element and rear part having coacting means for limiting the shifting of the carrier in the opposite direction. 10
13. In wind musical instruments of the reed type, a mouth pipe tube having a peripheral shoulder intermediate its ends and its inner face of uniform taper from its forward to its rear end, that portion of the outer face of said tube from said shoulder to its forward end being of uniform diameter, that portion of the outer face of said tube from said shoulder to its rear end being of uniform taper, a bearing mounted on said tube rearwardly of said shoulder, a shiftable mouth piece carrier including a forward part mounted against said portion of uniform diameter for carrying the mouth piece and a rear part mounted against said bearing, and a carrier shifting element revolubly mounted on the tube rearwardly of the bearing and encompassing and threadedly engaging with said rear part for shifting the carrier when said element is revolved, and said bearing and rear part having coacting means for slidably connecting the latter to the former. 15
14. In wind musical instruments of the reed type, a mouth pipe tube formed of a rear and a forward section, the latter having its rear portion outset for receiving the forward portion of the rear section, said outset rear portion completely encompassing said forward portion and providing a bearing, a shiftable mouth piece carrier including a forward part mounted against the forward portion of said forward section and a rear part mounted against said bearing, a carrier shifting element revolubly mounted on said rear section rearwardly of said bearing 70 and encompassing and threadedly engaging with said rear part for shifting the carrier when said element is revolved, and said bearing and rear part having coacting means for slidably connecting the latter to the former. 75
- In testimony whereof, I affix my signature hereto.
